UNITED STATES PATENT OFFICE

161,421

TOY GUN

John F. Carssow, Birmingham, Ala.

Application June 13, 1949, Serial No. 3,228

Term of patent 14 years

(Cl. D34—15)

To all whom it may concern:

Be it known that I, John F. Carssow, a citizen of the United States, residing at Birmingham, in the county of Jefferson and State of Alabama, have invented a new, original, and ornamental Design for Toy Gun, of which the following is a specification, reference being had to the accompanying drawing, forming part thereof, in which Fig. 1 is a fragmentary top plan view of a toy gun showing my new design; Fig. 2 is a side elevational view thereof; and Fig. 3 is a front end view. The other side of the gun, not shown, is substantially like the side shown but without the crank.

The handle of the crank is broken away in Fig. 1 for convenience of illustration.

I claim:

The ornamental design for a toy gun, as shown and described.

JOHN F. CARSSOW.
